CONCRETE FORM TIEROD AND FASTENING
THEREFOR

Samuel S. Colt, Orange, N. J.

Application February 6, 1932, Serial No. 591,317

8 Claims. (Cl. 25—131)

This invention relates to improvements in tie-rods for securing in assembled relation forms for casting concrete structures, and the invention further relates to fastenings for such tie-rods.

5 It has long been the practice to employ solid tie-rods for extension between the walls of concrete forms, together with means for fastening such tie-rods relative to the form walls. Great difficulty has been experienced, however, in withdrawing such tie-rods from the concrete, after the latter has set and preparatory to dismounting the form; this being due to the fact that the tie-rods, being imbedded in the set concrete, would adhere to or bind against the concrete, and would consequently offer great frictional resistance to withdrawing movement.

The present invention has for its principal object to provide a novel form and construction of tie-rod means comprising a multiple of separate 20 and separable sections so assembled and arranged as to offer a minimum of frictional resistance to withdrawal thereof from set concrete.

This invention has for a further object to provide a specific form of multiple section tie-rod 25 means having a wrapping of paper associated therewith to reduce friction incident to withdrawal thereof from the concrete.

A further object of this invention is to provide means associated with the tie-rods adapted to 30 utilize the same as spreader means for spacing form walls when the tie-rods are secured by their fastening means in assembled relation to the latter.

Other objects of this invention, not at this 35 time more particularly enumerated, will become apparent in the following detailed description of the same.

Illustrative embodiments of this invention are shown in the accompanying drawings, in 40 which:—

Fig. 1 illustrates one form and arrangement of the novel multiple section tie-rod of this invention assembled in holding relation to form walls, and also provided with the means for utilizing the assembled tie-rod as a wall spacing or spreader means; Fig. 2 is a horizontal section of the assembly shown in Fig. 1, taken on line 2—2 in said Fig. 1; Fig. 3 is a detail transverse section, taken on line 3—3 in Fig. 1, but drawn on an enlarged scale, the same illustrating one method of applying the paper wrapping to the tie-rod means; and Fig. 4 is a detail transverse section, taken on line 4—4 in Fig. 1, and also drawn on an enlarged scale.

55 Fig. 5 is an enlarged fragmentary side eleva-

tion of the novel tie-rod means, showing a modified arrangement of paper wrapping applied thereto; and Fig. 6 is a transverse section, taken on line 6—6 in Fig. 5.

Fig. 6^A is a transverse section, similar to that 60 of Fig. 6, but showing another modified arrangement of paper wrapping as associated with the multiple section tie-rod means.

Fig. 7 is a fragmentary side elevation of another modified form of multiple section tie-rod 65 means according to this invention; and Fig. 8 is a transverse section thereof, taken on line 8—8 in Fig. 7.

Fig. 9 is another fragmentary side elevation showing a further modified form and arrangement of multiple section tie-rod means; and Fig. 10 is a transverse section thereof, taken on line 10—10 in Fig. 9.

Similar characters of reference are employed in the above described views, to indicate corresponding parts.

Referring to the drawings, the use of the novel tie-rod means and fastening devices therefor are shown in connection with a common type of concrete wall form, although it will be understood that the same is applicable to many other specific types of forms. The wall form shown comprises, laterally spaced side members 11 provided with the usual externally applied battens 12. The side members 11 and battens 12 are respectively 80 provided with the holes or perforations 13 and 14 through which may project the ends of the tie-rod means, to which ends the fastening devices 85 are applied.

In the arrangement shown in Figs. 1 to 4 inclusive, the novel multiple section tie-rod means comprises a pair of half-round rod sections 15 and 16 disposed with their flat faces mutually opposed. Such two piece form of tie-rod means is preferable for most uses, but it will nevertheless be understood that the tie-rod means may be made up of more than two sections, if desired. One of the tie-rod sections, as 15, is provided intermediate its ends with an enveloping wrapping of flexible sheet material 17, the longitudinal marginal portions 18 and 19 are preferably overlapped one upon the other so as to overlie the flat face of the section 15, and so as to be interposed between the opposed flat faces of the sections 15 and 16 when operatively assembled together. Sheet paper has been found to afford a very satisfactory sheet material for the wrapping, although any other flexible material may be employed if desired. The lapped marginal portions 18—19 of the wrapping serves to space 100 105 110

slightly apart the intermediate portion of the multiple section tie-rod, whereby the end portions of the latter taper somewhat toward their extremities, which emerge from the form interior, 5 so as to project exteriorly beyond the side members 11 and through the battens 12.

Suitable fastening devices are engaged with the exteriorly projecting ends of the tie-rod means. Preferably the fastening devices comprise a wedge 10 abutment block 20 having a longitudinal or axial opening 21 therethrough, and being further provided, adjacent to its outer end, with an internally threaded laterally projecting boss 22 to receive a set-screw 23. Provided at the inner end of 15 said wedge abutment block 20 are laterally off-set forwardly projecting wings 24 having inwardly projecting keeper lugs 25 at their free ends. A wedge member 26 is arranged for longitudinal vertical movement between the wings 24 and 20 against the end of said abutment block 20. This wedge member is provided with a longitudinal through slot 27 which registers with the opening 21 of the abutment block 20, whereby a projecting end portion of the tie-rod means may extend 25 through these parts. The wedge member is also provided along its inclined rearward face with marginal flanges 28 which engage beneath the keeper lugs 25, thus retaining the wedge and block in assembled relation, subject to the operative movement of the wedge relative to the block. 30 When the wedge and block are mounted over and upon a projecting end portion of the tie-rod means, and the wedge, as raised, having its vertical face abutting the batten 12, the set-screw 35 23 is screwed home to lock the block immovably upon the tie-rod means, whereupon the wedge may be driven downward to bring home and hold the side members 11 in operative set up relation to the form of which they provide necessary parts. 40

In order to permit the tie-rod means to also function as spreader means for spacing the side members 11 and holding the same against inward displacement preparatory to casting concrete 45 therein, tiltable rod gripping stop elements are arranged upon the rod ends. These tiltable stop elements comprise a gripping plate 29 having an opening 30 in its body through which the tie-rod means may extend, and said opening 30 having, at its upper and lower edges, gripping portions 31 adapted to grip the tie-rod means when the plate 50 is canted or tilted to operative position, thus rendering the plate immovable relative to the tie-rod means. Extending from the upper end of said gripping plate 29, and preferably integrally formed therewith, is an angular extension or arm 32. If desired, side webs 33 may be provided 55 between the plate and extension or arm adapted to prevent poured concrete from entering beneath and within the angle of these parts. When assembling the tie-rod means with the form, the gripping plates 29 are engaged on the end portions 60 of the former so as to be disposed for engagement by the inner faces of the side members 11. The side members 11, when operatively set up by the above described operation of the exteriorly applied wedge and block, abut the arms or extensions 32, tending to thrust inwardly thereupon, thus causing the plate 29 to tilt whereby the gripping portions 31 bind upon the tie-rod means 65 to immovably lock the stop elements thereto so as to resist and stop any inward displacement of the side members of the form, and consequently the latter are held immovably spread or laterally spaced apart at desired distance. 70

After the form has been assembled and locked 75

up in the manner above indicated, and the concrete has been poured thereinto and set, the form may be dismantled by removing the wedge and block fastenings from the ends of the tie-rod means, and the side members 11 and battens 12 thereupon 80 may be removed from the concrete structure. This having been done, the tie-rod means are exposed for withdrawal from the structure. If the tiltable rod gripping stop elements have been used, the same will be exposed at the 85 surface of the concrete, and are first removed by chipping out the same, so that they may be loosened and withdrawn. The next step will thereupon be to withdraw the tie-rod means. Owing to the multiple section structure of the 90 tie-rod means, this may easily be done by driving or pulling one section longitudinally relative to the other. Because of the paper wrapping, the section 15 may be easily so driven or pulled, since the paper provides a surface against which the 95 rod section may move with a minimum of frictional resistance, both with relation to the surrounding concrete mass as well as with relation to the other section 16. Once one section is thus removed, the remaining section may be 100 quickly and easily removed, as will be obvious.

In Fig. 3 I have shown but one section of the tie-rod means provided with the wrapping; in a modified arrangement, however, as shown in Figs. 5 and 6, both sections 15—16 of the tie-rod 105 means may be enveloped in the wrapping, preferably by inserting a marginal portion 34 of the wrapping between the rod sections and then winding the remainder of the wrapping about both rod sections to form a complete encircling 110 wrapping 35. It is not absolutely essential to insert a lap of the wrapping material between the rod sections, for the latter may be merely enveloped in an externally encircling wrapping 36, as shown in Fig. 6A. 115

In the broader aspects of my invention, the same resides mainly in the provision of the tie-rod means in multiple section form, with or without the wrapping of flexible material such as paper. When the multiple section tie-rod is 120 employed without the wrapping, it is preferable that the rod sections be slightly outwardly bowed with respect one to another. Such bowing renders the rod sections somewhat laterally yieldable. This is of advantage, since when concrete 125 is poured into the form and around the tie-rod means, the concrete tends to shrink or contract somewhat so that, in cases where solid one-piece rods are used a very strong frictional binding of the set concrete relative to the surfaces of 130 the rod occurs. When using the multiple section tie-rod of this invention, and especially when the sections are somewhat bowed as above mentioned, the rod sections will yield to the shrinkage or contraction of the concrete, 135 and consequently the objectionable strong frictional binding effect referred to will not occur, and the rod sections may be easily and quickly withdrawn from the set concrete. Even where the wrapping is interposed between the rod sections, such yielding effect is still obtained, since the wrapping material is per se comparatively soft and more or less compressible. 140

In Figs. 7 to 10, inclusive, I have shown an arrangement of multiple section tie-rod without 145 wrapping, but having the bowed form above referred to. In Figs. 7 and 8, I have also indicated that one or more of the rod sections may be provided on their meeting faces with small protuberances, as 37, which serve as initial spac- 150

ing means for spacing the rod sections somewhat apart in the desired bowed relation. These protuberances are made by up-setting the rod material at the desired surface upon which the 5 same are to be provided. Such up-setting may be produced by a nail punch or any other suitable tool. When removing a multiple section tie-rod means, having such protuberance, by driving or pulling one rod section relative to the other, 10 the protuberance will be quickly smoothed down or leveled by the relative movement of the sections one against another, and will offer but negligible resistance to the movement of the manipulated rod section.

15 In Figs. 9 and 10 I have shown the arrangement of multiple section tie-rod means without wrapping but having the preferable bowed form, and in connection therewith I have shown a retaining ring 38 which initially holds the rod sections together in operative assembled relation. It will be obvious, that after the concrete 20 has set about the rod sections, the ring 38 will be imbedded therein, and that consequently the rod sections may be easily driven or pulled away 25 from and out of the concrete.

I am aware that variations, other than those already mentioned, may be made in the above described constructions and many widely different embodiments of this invention could be made without departing from the scope thereof; it is intended, therefore, that all matter contained in the above description and shown in the accompanying drawings shall be interpreted as illustrative and not in a limiting sense.

Having thus described my invention, I claim:

1. In apparatus of the kind described, a tie-rod means comprising a plurality of separable sections assembled in registered and aligned single rod forming relation, one or more of said sections being longitudinally bowed to somewhat space the sections apart intermediate their ends, and a wrapping of sheet material enveloping one or more of said sections intermediate the ends

45 2. In apparatus of the kind described, a tie-
rod means comprising a pair of half-round sec-
tions assembled in registered and aligned single
rod forming relation and with their flat faces
opposed one to the other, said sections being out-
wardly bowed to slightly space apart interme-
diate portions of their opposed flat faces, there-
by to reduce friction therebetween when said
sections are relatively moved longitudinally.

3. In apparatus of the kind described, a tie-
rod means comprising a pair of half-round sec-
tions arranged with their flat faces toward one
another, and a wrapping of paper around at least
one of said sections intermediate its ends.

4. In apparatus of the kind described, a tie-
60 rod means comprising a pair of half-round sec-
tions arranged with their flat faces in opposition,
a wrapping of paper to envelope said sections
intermediate their ends, said wrapping having
a portion thereof disposed between the opposed
65 flat faces of said sections.

5. In apparatus for assembling a form including spaced side members, a tie-rod means extending through and between said side members, a gripping element having an opening therethrough to pass said tie-rod means and having an angular extension at one end to about

the inside face of a side member whereby inward moving pressure exerted upon the latter tilts said gripping element into immovable bound relation to said tie-rod means to thereby hold said side member against inward displacement, and means engaged with the portion of said tie-rod means exteriorly projecting from said side member to press and hold the latter toward and into engagement with said angular extension of said gripping element.

6. In apparatus for assembling a form including spaced side members, a tie-rod means extending through and between said side members, a gripping element having an opening therethrough to pass said tie-rod means and having an angular extension at one end to abut the inside face of a side member whereby inward moving pressure exerted upon the latter tilts said gripping element into immovable bound relation to said tie-rod means to thereby hold said side member against inward displacement, and means engaged with the portion of said tie-rod means exteriorly projecting from said side member to press and hold the latter toward and into engagement with said angular extension of said gripping element, said latter means comprising an abutment block fixed on said tie-rod means and a wedge member movable between said abutment block and said side member. 100

7. In apparatus for assembling a form including spaced side members, a tie-rod means comprising a plurality of separable sections assembled in registered and aligned rod forming relation, said tie-rod means extending through and between said side members, a gripping element having an opening therethrough to pass said tie-rod means and having an angular extension at one end to abut the inside face of a side member whereby inward moving pressure exerted upon the latter tilts said gripping element into immovable bound relation to said tie-rod means to thereby hold said side member against inward displacement, and means engaged with the portion of said tie-rod means exteriorly projecting from said side member to press and hold the latter toward and into engagement with said angular extension of said gripping element. 105 110 115 120

8. In apparatus for assembling a form including spaced side members, a tie-rod means comprising a plurality of separable sections assembled in registered and aligned rod forming relation, said tie-rod means extending through and between said side members, a gripping element having an opening therethrough to pass said tie-rod means and having an angular extension at one end to abut the inside face of a side member whereby inward moving pressure exerted upon the latter tilts said gripping element into immovable bound relation to said tie-rod means to thereby hold said side member against inward displacement, and means engaged with the portion of said tie-rod means exteriorly projecting from said side member to press and hold the latter toward and into engagement with said angular extension of said gripping element, said latter means comprising an abutment block fixed on said tie-rod means and a wedge member movable between said abutment block and said side member.

SAMUEL S. COLT. 145
